GOGGLE

Fred G. Gay, Jr., Greece, and Walter O. Parker, Henrietta, N. Y., assignors to Bausch & Lomb Optical Company, Rochester, N. Y., a corporation of New York

Application June 11, 1957, Serial No. 46,548

Term of patent 7 years

(Cl. D57—1)

FIG. 1

FIG. 2

FIG. 3

FIG. 4

FIG. 5

Fig. 1 is a rear perspective view of a goggle showing our new design.

Fig. 2 is a front perspective view of same.

Fig. 3 is a top plan view thereof.

Fig. 4 is a front elevational view thereof.

Fig. 5 is a side elevational view thereof.

The temples are shown broken away in Figs. 1, 2, 3 and 5 for convenience of illustration.

The characteristic features of our design for the goggle disclosed reside in the configuration of the goggle front portion as shown.

We claim:

The ornamental design for a goggle, substantially as shown and described.
